UNITED STATES PATENT OFFICE

1,973,436

METHOD OF MAKING BOBBIN RINGS

John F. Hjort, Worcester, Mass., assignor to
The American Steel and Wire Company of
New Jersey, a corporation of New Jersey

Application August 28, 1931, Serial No. 560,003

2 Claims. (Cl. 29—170)

This invention relates to an improved method of making bobbin rings. The practice most generally followed in making bobbin rings for the textile industry is to feed the wire stock from which the rings are produced into a forming machine, the wire being cut in suitable lengths and then bent around a mandrel of suitable diameter.

As will be understood by those skilled in the art, the purpose of the bobbin rings is to protect the head of the bobbin from breakage, and provide a suitable means for removably holding the bobbin in a shuttle. The shuttle is provided with a pair of flat grooved springs at one end, which springs are provided with grooves to receive the bobbin rings. When the bobbin is forced into the shuttle the flat springs open up or spread and allow the rings on the head of the bobbin to enter the grooves, thereby holding the bobbin in its proper position while the shuttle is in operation.

When the bobbins are stripped or removed from the spinning frames they are thrown into trucks, and no care is taken to prevent the 25 rings of one bobbin from coming in contact with the yarn on another bobbin. This is very serious, since when rough rings are used they snag the 30 yarn of the other bobbins, and cause snarls and tangles and otherwise damage the yarn so that it must be destroyed.

35 It is desirable that the ends of the rings be perfectly smooth and substantially closed when assembled on the head of the bobbin. Heretofore the rings provided for this purpose had a rough jagged surface in cross-section, while the rings produced by this invention have a smooth end and will not snag the yarn on their own or on another bobbin.

It has been found that the foregoing defects
40 result from the method of cutting the ends
of the lengths of wire from which the rings are
formed.

If the wire is cut squarely where the ends of the rings join a pinching action takes place and these ends will, in most instances, present a rough jagged surface in cross-section and the inner contour of the ring will be irregular or dipped at this point. If, however, the ends of the wire are sheared or cut at an angle on a plane inclined toward the inner curvature of the ring and without a pinching-in action, the inner curvature of the ring will remain substantially unbroken and the ends of the wire will present a smooth cross-sectional surface contour.

The present method of producing bobbin rings, therefore, consists broadly in bending suitable lengths of wire in the form of a ring and shearing or cutting the ends of the wire at an angle or plane inclined toward the inner curvature of the ring.

The resultant product is a bobbin ring having a regular, substantially unbroken, inner surface curvature and beveled ends which present a smooth rounded contour in cross-section. 65

The drawings illustrate a preferred type of mechanism and manner of carrying out the method in successive steps but it will be understood that any desired tools or mechanism, as well as any desired sequence of operations, may be adopted without departing from the scope of the invention. 70

In the drawings: Figures 1 to 5, inclusive, illustrate a mandrel and a set of tools and the various positions thereof during the successive steps of the method. 75

Figures 6 and 7 illustrate preferred types of

cutting tools. 22

Figure 8 illustrates the finished product. Figure 9 is a plan view of a shuttle and bobbin.

Figure 10 is a plan of the bobbin removed

Figure 11 is a continuation of Figure 6 (3) and is 85.

Figure 11 is a perspective view of the bobbin receiving spring end of the shuttle.

The reference numeral 5 designates a shaping mandrel formed with a reduced end or extremity 5^a, (note Figure 4) 6 a binding tool, and 7, 8, 9 and 10 shaping tools or dies which cooperate to press the wire around the mandrel; 12 designates male cutting or shearing tools and 13 and 13^a female cutting or shearing tools.

Figure 1 illustrates the first operation, the wire being fed into the machine over the small end portion 5^a of the mandrel 5 and cut, leaving squared ends, the binding tool 6 holding the wire in place. The female tool 13^a has a double cutting edge to provide for this initial severing operation.

After the wire is cut, tool or die 7 bends the wire to an angle of approximately thirty degrees as shown in Figure 2, and cutting tools 12, 13 and 13^a then move into cutting or shearing relation and shear off the ends of the wire at an angle, leaving a rounded and beveled end.

The cutting tools are illustrated in Figs. 6 and 7, Figure 6 showing the male cutting tools and

Figure 7 the female tools. The design of these tools is such that they produce the rounded beveled end cut or shear above specified. The ends of the said tools are tapered and the 5 male tools are formed with a rib 14 on the cutting extremity while the female tools are formed with a semicircular recess 15. As the tools move together in cooperative shearing relation, the opposite extremities of the wire are 10 caught in the recesses 15 of the female tools 13 and 13^a, and forced against the tapered ends of the male cutting tools with the squared ends on the ribs 14. The ends of the wire are thus sheared at an angle and simultaneously rounded 15 and beveled (note Figure 8).

After the ends of the wire are sheared as just specified, tool or die 7 bends the wire around the small end 5^a of the mandrel 5 to the position shown in Figure 3.

20 Shaping tools 9 and 10 then move toward the mandrel and form the wire into an approximate pear shape, as shown in Figure 4. These tools then move back or retract and tool or die 7 releases the wire sufficiently to permit 25 the mandrel 5 to move further into the partly formed ring and expand the latter over the enlarged portion of the mandrel, as shown in Figure 4^a. This operation increases the diameter of ring to the desired size and reverses the 30 internal strain of the wire to an inward recoil, thus providing for the production of a ring with closed ends when using a high carbon grade of steel which is slightly annealed.

The final operation is shown in Figure 5, tools 35 8, 9 and 10 moving into cooperative relation with the mandrel and completing the ring as illustrated in Figure 8.

In order to illustrate the use of the rings produced by this invention I have shown a shuttle and bobbin assembly in Figure 9, and details 40 of the bobbin and spring forming parts of the assembly in Figures 10 and 11.

The shuttle consists of a body portion 20 which is reduced in cross-section to form pointed 45 ends 21, each of which is provided with a metal tip 22. The body of the shuttle 20 is

hollowed out as at 23 to form a bobbin receiving opening, and is provided with a clevis-like spring member 24 at one end, which has its arms extended parallel with the sides of the body portion and is provided with grooves 25 to receive the rings 26 carried by the head 27 of the bobbin 28.

The rings 26 fit snugly in grooves formed in the head 27 of the bobbin 28, and serve the dual purpose of binding member to prevent splitting of the heads and attaching members for securing the bobbin to the spring 24.

The above described shuttle and bobbin construction is of standard, well known design, and will not be described further in detail, since it 90 does not form any part of this invention.

What is claimed as new is:—

1. A process of producing bobbin rings, including providing a suitable length of wire, restraining the central portion of said wire, applying similarly directed forces right-angularly to either side of said central portion of said wire to bend the latter's end portions until they are at an angle to each other, shearing the ends of said wire in directions substantially the same 100 as those of said forces and applying further forces to said wire directed to bend it to ring form with its ends in mutually abutting relationship.

2. A process for producing bobbin rings, including providing a suitable length of wire, associating a round object with the central portion of said wire, applying forces right-angularly to said wire at either side of said object and directed theretowards so as to bend the wire's 110 end portions until they are at an angle to each other, shearing the ends of said wire in directions substantially the same as those of said forces, applying forces to bend said wire about said round object sufficiently to bring its ends 115 adjacent, removing said object from said wire so bent and substituting a larger round object in its place and bending said wire to ring form about said object with its ends in mutually abutting relationship.
